UNITED STATES PATENT OFFICE.

WILLIAM PATTERSON, OF WINCHESTER, ILLINOIS.

CLOTHESPIN.

1,356,785.

Specification of Letters Patent. Patented Oct. 26, 1920.

Application filed August 19, 1918. Serial No. 250,528.

To all whom it may concern:

Be it known that I, WILLIAM PATTERSON, a citizen of the United States, residing at Winchester, in the county of Scott and State 5 of Illinois, have invented new and useful Improvements in Clothespins, of which the following is a specification.

This invention relates to improvements in clothes pins, the object of the invention 10 being to provide an improved clothes pin which is extremely durable and which can be readily manufactured at slight cost.

With the above and other objects in view, the invention consists in the construction, 15 combination and arrangement of devices hereinafter described and claimed.

In the accompanying drawings:

Figure 1 is an elevation of a clothes pin constructed and arranged in accordance 20 with my invention.

Fig. 2 is a longitudinal sectional view of the same.

Fig. 3 is a transverse sectional view of the same.

25 My improved clothes pin comprises a pair of substantially semi-tubular members 1, which are made of thin sheet metal, preferably tin, and each of which is formed at opposite sides and at a point intermediate 30 its ends with lugs 2. Each member has a jaw 3 at one end and an arm 4 at the opposite end and the arms of the members are slightly curved so that they diverge outwardly, as shown.

35 The members are pivotally connected together by a pin 6 which passes through openings in the lugs. A spring 7 has a coiled portion 8 which is arranged around the pivoting pin and has arms which bear 40 against the inner sides of the arms of the members 1. A pair of gripping members 9 which are made of wood are arranged in the

jaws of the members 1 and secured thereto as by means of rivets 10. The gripping members have coengaging serrations 11 in 45 their opposing sides to firmly grip the clothes and are also provided with transverse grooves 13 for the passage of the clothes line. The spring serves to normally close the jaw and to hold the gripping members 50 firmly engaged with the clothes and on the line, as will be understood. The wooden gripping members project beyond the inner sides of the sheet metal semi-tubular members 55 1, prevent said sheet metal members from coming in contact with the line or the clothes, and hence prevent injury to the line or the clothes by rust.

My improved clothes pin is extremely 60 strong and durable and may be readily manufactured at slight cost.

Having thus described my invention, I claim:

A clothes pin comprising a pair of members of concavo-convex cross-sectional shape, 65 arranged with their concaved sides opposed and provided at a point intermediate their ends with lugs at opposite sides, a pivot pin extending through openings in the lugs and pivotally connecting the members together, 70 gripping blocks secured within the concaved sides of the members and extending beyond the side edges thereof, said gripping blocks being provided upon their opposed faces with interengaging teeth or serrations 75 extending across the width of the block and having a substantially semi-tubular recess located adjacent the pivotal connection to provide a clothes line grip and a spring for normally holding the teeth or serrations in 80 gripping or engaged position.

In testimony whereof I affix my signature.

WILLIAM PATTERSON.
